UNITED STATES PATENT OFFICE.

HORACE B. GALE, OF NATICK, MASSACHUSETTS.

ELECTRIC LIGHTING APPARATUS.

SPECIFICATION forming part of Letters Patent No. 319,573, dated June 9, 1885.

Application filed March 27, 1885. (No model.)

To all whom it may concern:

Be it known that I, HORACE B. GALE, a citizen of the United States, residing at Natick, in the county of Middlesex and State of Massachusetts, have invented certain new and useful Improvements in Electric Lighting Apparatus, of which the following is a specification, reference being had to the drawings accompanying and forming a part of the same.

10 My invention is an apparatus for use in electric lighting systems or circuits in which the lamps, or it may be other electrical devices, are connected in series.

The main purpose of the device is to provide 15 a ready means for restoring the continuity of the circuit through a series of lamps when it has been interrupted from any accidental cause, such as the breaking of a lamp, the object being to relight all the lamps but the 20 defective one. The latter is thus identified, and may be at once replaced. It will be seen, however, from the description which follows, that the invention serves other useful purposes, and may be used not only with arc or 25 incandescent lamps or their equivalents in an ordinary series circuit, but is also useful in the cross-circuits of a system in which the translating devices are connected in series. I have found the invention to be more practicable and useful in connection with a series of 30 incandescent lamps, and I have illustrated it as applied to them. When any lamp in a series gives out, either through the destruction of its carbon or other cause, the continuity of the circuit is interrupted, and all the 35 other lamps are extinguished, which often makes it a difficult matter to ascertain which one of the series of lamps has failed in order to replace it. It has been the custom heretofore to provide each lamp with a resistance and cut-out, or a device that brings into the 40 circuit a resistance equivalent to the lamp when the latter is extinguished. By my apparatus I dispense with the resistance commonly used for replacing lamps, and produce a cheaper and equally practicable means for 45 replacing the extinguished lamp. I use for this purpose a series of insulated terminals and a connecting device—preferably a sliding 50 contact-strip—capable of connecting any two adjacent terminals. These terminals are permanently connected with the circuit at points

between the lamps included therein. By this means, when a lamp is extinguished and the circuit is broken, it will be closed again when 55 the sliding contact bridges the terminals that complete a shunt about the extinguished lamp. By some distinctive features this position of the contact may be made to indicate the defective or exhausted lamp, which may be 60 readily replaced. I may operate the contact by hand, or partly by hand and partly by mechanical devices automatic in their action, or entirely by automatically-operating mechanism; and without adding materially to the 65 number of parts or the difficulty of operating the device I may provide for maintaining in the circuit the same resistance when the circuit is closed after the destruction of a lamp as before, and for securing other useful results, the nature of which will be hereinafter more fully set forth.

Figure 1 of the accompanying drawings represents a simple embodiment of my invention adapted to be operated by hand. Fig. 2 is a 75 modification of the same, partly manual and partly automatic; and Fig. 3 is a second modification of an automatic apparatus by means of which the invention is or may be carried into effect.

Referring to Fig. 1, L^2 L^3 L^4 L^5 represent electric incandescent lamps or other similar translating devices arranged in series in a given circuit. Should one of these lamps give out, all the others are extinguished, and it 85 would be a matter perhaps of difficulty to ascertain which one of the series of lamps had been extinguished. To ascertain this readily I use an apparatus which consists of a series of metal contacts or terminals, as a b c d e f , secured to a suitable base, and these are connected with the circuit m n at points between the lamps in regular order or succession.

In conjunction with the contacts a b c , &c., is a pivoted arm, h , carrying a metal strip or 95 spring-plate, k , that bears against the contacts. The strip k is capable of spanning any two adjacent contacts or plates, but not more. If one of the lamps, as L^4 , be extinguished, so that all the rest go out, the circuit will be re-established by turning the arm h until plates d e are connected, these being the terminals of a shunt around the lamp L^4 . All the lamps except L^4 are thus relighted. The defective

- or exhausted lamp is thus at once indicated, and may be replaced by one of the several lamps, as L L' , which, as a matter of convenience, are kept on brackets on the apparatus.
- 5 The circuit may then be restored to its original condition by moving the connecting-arm back to its normal position at h .
- As it may often be desirable to keep a uniform resistance in the circuit m n when the 10 lamps are running, I use a lamp, L' , in series with the others, which is, however, short-circuited by the strip k in its normal position. This lamp is preferably placed on or near the apparatus, and not only takes the place of one 15 which may give out, but indicates, by becoming incandescent, when the circuit is closed through the others by the strip k . In lieu of this lamp an ordinary resistance-coil may be used, or resistances r r' may be used in addition 20 to it to prevent the full flow of current through it. The arrangement of the resistances r r' in derivation, as shown, also provides a path for the current should the lamp L' give out. The series of lamps are connected with the generator or feeding-main l by a switch, g , that is 25 arranged to bear on contact-terminal a . In order to reduce the amount of light given by the lamps, the arm h may be turned to any position, in which it rests in contact with only 30 one of the terminals. The lamp L' or other suitable resistance is thus added to the circuit.
- The apparatus may also be used to put out any one lamp of a series without affecting the others by placing the handle in the proper position to short-circuit that lamp.
- 35 In Fig. 2 the arm h is carried by a shaft, to which motion is transmitted by a volutespring, S . By means of a ratchet-wheel fixed on the shaft with the arm h , and a pawl carried by a 40 gear-wheel, otherwise free on the shaft, this motion may be communicated through a train of gears to the shaft p , carrying a fan, w , to retard the motion of the train, and to an iron disk capable of a certain vertical movement 45 in its bearings, and arranged to revolve between the poles t t of an electro-magnet. When the current is flowing through the lamps, the disk is held against the poles t , and the train of gears locked. Should a lamp give out, the 50 disk u is dropped, and the train set in motion, the arm h being thereby turned until it bridges or spans the contacts connected with the circuit on opposite sides of the defective lamp. The moment that this takes place the magnet 55 is again rendered active and the train again locked. When the lamp is replaced, the arm h may be turned back to its normal position without turning the disk u , by reason of the ratchet and pawl.
- 60 A device for interrupting the circuit through the lamps is here shown, that consists of a spring, g , that bears against a stop, x . When the arm h has moved into the position in which strip or spring k bears only on the last terminal, f , a pin, p , on arm h comes in contact with spring g , and moves it into the position shown at g' . The circuit being still main-

tained to spring g , through the metal arm h , is broken when the strip k leaves the terminal f . In this way a spark at X is prevented. As 70 the arm h cannot be moved to the right unless the disk u be free to move, and as it may be sometimes desirable to so move it, to introduce the additional resistance of lamp L' , for example, I combine with the magnet that locks 75 the disk u a shunting or short-circuiting key, y .

It is evident that the operation of the device above described depends upon the cessation of current in circuit m n , which may be due either to the failure of a lamp or the stopping of the dynamo. Whenever the arm is set in motion by any cause outside of the series of lamps controlled by the switch, it will move around until it strikes a stop, z , thus breaking the circuit through the lamps. Before the lamps can be lighted again it is necessary to set the handle back to the position shown in unbroken lines.

In Fig. 3 I have shown a device which, by the addition of a second magnet, is caused to 90 operate only by the interruption of the circuit at some point in the series of lamps, as by a failure of one of the latter. This device consists of an electro-magnet, t' , which, when excited, raises its armature, which is arranged 95 as a locking-pawl, and releases a ratchet-wheel on the shaft-carrying arm h and impelled by a spring, as before described. This magnet is in a circuit from the arm h and the armature of magnet t' , the coil of which is in 100 series with the lamps. The circuit through magnet t' is broken while magnet t' is energized, but is closed as soon as it becomes inactive. If a lamp fails, the magnet t' is energized and the arm h permitted to turn. As soon 105 as the strip which it carries closes the circuit around the extinguished lamp, however, the magnet t' is energized and the ratchet-wheel controlled by magnet t' is locked.

It is now obvious that the mechanism entering into this invention may be very greatly varied, and I do not confine myself, therefore, to any of the specific forms shown and described.

What I claim is—

1. The combination, with a series of electric lamps, of a group of terminals, means for connecting said terminals, and electrical connections from the terminals to the circuit, whereby a path for the current may be closed 110 around each of the lamps successively, as and for the purpose set forth.

2. The combination, with a series of electric lamps, of a group of insulated terminals connected to points of the circuit between the 115 lamps, a movable contact for connecting the terminals, and a device carrying said contact, whereby a path for the current may be closed around each of the lamps successively, as herein set forth.

3. The combination, with a series of electric lamps, of a group of terminals connected to the circuit in the manner described, a movable contact-maker for connecting said termi- 120 125 130

nals and successively shunting each lamp, a circuit-breaker in the lamp-circuit, and manual or automatic means for operating both the contact-maker and circuit-breaker, substantially as herein set forth.

4. The combination, with a series of electric lamps, of a group of terminals connected with the circuit in the manner described, a contact-maker for connecting the terminals, and thereby shunting the lamps successively, and a lamp or its equivalent in the circuit between the two terminals, connected by the contact-maker in its normal position when the circuit through the series of lamps is complete, as herein set forth.

5. The combination, with a series of electric lamps, of a group of terminals connected with the circuit in the manner described, a contact-maker for connecting the terminals, and thereby shunting the lamps successively, impelling mechanism—such as a spring—for

moving said contact-maker, and one or more electro-magnets for controlling the action or operation of the impelling mechanism, as herein described.

6. The combination, with a series of electric lamps, of a group of terminals connected with the circuit in the manner described, a contact-maker for connecting the terminals, and thereby shunting the lamps successively, impelling mechanism—such as a spring—for moving the contact-maker, an electro-magnet in the lamp-circuit for controlling the action or operation of the impelling mechanism, and a circuit around said magnet with means for controlling the same, as set forth.

In testimony whereof I have hereunto set my hand this 7th day of March, 1885.

HORACE B. GALE.
